PRODUCTION OF 3-INDOLE ALDEHYDE

Edgar C. Britton, John E. Livak, and John C. Vander Weele, Midland, Mich., assignors to The Dow Chemical Company, Midland, Mich., a corporation of Michigan

No Drawing. Application October 23, 1944,
Serial No. 560,034

6 Claims. (Cl. 260—319)

1

This invention concerns an improved method for the production of 3-indole aldehyde.

It is known that 3-indole aldehyde may be formed by reacting indole with a lower alkyl magnesium iodide to form indole magnesium iodide, adding ethyl formate and heating to 70° to 100° C. However, by-products, particularly N-formyl-indole, are formed in considerable amount and the yield of the aldehyde is low. It has heretofore been usual practice to add, to a solution of the indole magnesium iodide, approximately five molecular equivalents of ethyl formate and to heat the resultant mixture at atmospheric pressure to the reaction temperature. Putochin, Ber. 59 1991 (1926) indicates that when operating in this manner, the yield of 3-indole aldehyde is between 27 and 33 per cent of theoretical.

It is an object of this invention to provide an improved method whereby 3-indole aldehyde may be produced more economically and/or in higher yield than by the known method just mentioned. A particular object is to provide an improved method which will permit the use of an alkyl magnesium bromide, instead of an alkyl magnesium iodide, as a starting material in the production of 3-indole aldehyde. Other objects will be apparent from the following description of the invention.

We have found that a lower alkyl magnesium bromide, instead of a corresponding iodide, may be used in producing 3-indole aldehyde by the general reactions just mentioned, provided the reaction between the indole magnesium bromide (obtained as an intermediate product) and a lower alkyl formate is carried out at an elevated temperature and pressure in the presence of diethyl ether as a medium for the reaction. Peculiarly, attempts on our part similarly to employ alkyl magnesium chlorides in the process have not resulted in the formation of 3-indole aldehyde in an appreciable yield. We have also found that by carrying out the reaction between indole magnesium bromide and a lower alkyl formate under pressure and in ethereal solution, 3-indole aldehyde may be produced in a yield considerably higher than has heretofore been reported. We have further found that the five-fold molecular excess of an alkyl formate over an indole magnesium halide, heretofore employed in the reaction for formation of the 3-indole aldehyde, is unnecessary and that the aldehyde may be obtained in as good a yield when employing the formate in amount molecularly equivalent to, or only moderately in excess of, the indole magnesium halide. On a basis of these discoveries we have devised the following improved method for the production of 3-indole aldehyde.

A lower alkyl magnesium bromide is formed, as usual, by reacting magnesium with an ethereal solution of an alkyl bromide. The alkyl bromide

2

employed is one containing not more than four carbon atoms in the alkyl group, i. e. the alkyl group is one corresponding to a normally gaseous paraffinic hydrocarbon. Diethyl ether, in amount sufficient to dissolve the alkyl magnesium bromide, is used as a medium for the reaction.

The resultant ethereal solution of the lower-alkyl magnesium bromide is treated with indole in amount not exceeding the molecular equivalent of the alkyl-magnesium bromide. The indole and alkyl magnesium bromide react readily to form indole magnesium bromide and evolve a paraffinic hydrocarbon corresponding to the alkyl group of the alkyl magnesium bromide. The reaction is preferably carried out in a closed reactor at room temperature or thereabout with cooling and gradual withdrawal of the gaseous hydrocarbon as it is formed, since loss of the ether by vaporization may thus be minimized. However, the reaction may be carried out at lower or higher temperatures. When operating on a large scale, the indole is preferably added gradually and with stirring until the gaseous hydrocarbon is no longer evolved, at which time introduction of the indole is discontinued. It is important that the indole be employed in amount not greatly exceeding the molecular equivalent of the alkyl magnesium bromide, since excess indole, if present, reacts with the indole magnesium bromide intermediate product and consumes a portion of the latter with formation of undesired by-products.

The ethereal solution of indole magnesium bromide is treated with methyl formate, or preferably ethyl formate, in amount corresponding to between 0.8 and 2.5, preferably between 1.0 and 1.5, of the molecular equivalent of the indole magnesium bromide. The formate is usually added gradually and with stirring at room temperature or thereabout, but it may be added while heating the reaction mixture if desired. In any case, it is necessary that the mixture be heated within a short time, e. g. less than 3 hours, after adding the formate since the latter and the indole magnesium bromide react slowly at room temperature or lower to form principally N-formyl-indole rather than the desired aldehyde. The reaction mixture is heated in a closed vessel, e. g. a bomb or autoclave, at temperatures between 60° and 120° C., preferably at from 70° to 110° C. Usually, from 20 to 40 minutes of heating is sufficient to complete the reaction.

Thereafter, the vessel is cooled, opened, and ether is separated from the resinous reaction product. The latter is decomposed to liberate 3-indole aldehyde by procedure usual in the treatment of other Grignard reaction products. For instance, it may be ground or broken into small pieces, admixed with ice water and treated with an acid, preferably an aliphatic carboxylic

acid such as formic, acetic, or propionic acid, etc., to effect hydrolysis and liberate the aldehyde.

N-formyl-indole, present as a by-product, may be extracted from the aqueous mixture by agitating the latter together with a liquid aromatic hydrocarbon solvent. During the extraction, 3-indole aldehyde remains undissolved and tends to collect either at the interface between the liquid phases or to become admixed with the hydrocarbon phase. The major portion of the aqueous phase is then separated and the remaining mixture is filtered to recover the solid 3-indole aldehyde. N-formyl-indole may be recovered, e. g., by fractionally distilling the extract.

The products may, of course, be separated in other ways from the reacted mixture. For instance, the latter may first be filtered or decanted to separate 3-indole-aldehyde in crude form and the product may be purified by extracting, e. g., by steam distilling, N-formyl-indole therefrom.

The following example describes one way in which the principle of the invention has been applied, but is not to be construed as limiting the invention.

Example

An ethereal solution of ethyl magnesium bromide was prepared by a usual Grignard reaction between 12.15 parts (0.5 atomic weight) of magnesium shavings and 59.5 parts (0.55 mole) of ethyl bromide in the presence of 107 parts of diethyl ether. A solution of 50 parts (0.43 mole) of indole in 71.4 parts of diethyl ether was added to the ethyl magnesium bromide solution over a period of 30 minutes while maintaining the mixture in a closed vessel at temperatures between 20° and 30° C. and withdrawing ethane as it was formed by the reaction which occurred. Introduction of the indole solution was discontinued when the evolution of ethane ceased. Approximately 41 parts (0.55 mole) of ethyl formate was added over a period of 30 minutes to the ethereal solution of indole magnesium bromide thus formed and the resultant mixture was heated in an iron autoclave at a temperature of 95° C. for 30 minutes. The mixture was allowed to stand overnight without further heating, after which the autoclave was opened. The mixture comprised a hard reddish-brown resinous substance which has separated from the ether. The ether was poured from the resinous substance and the latter was pulverized, admixed with ice water and the mixture neutralized with acetic acid. The resinous Grignard reaction product was thereby decomposed with formation of an aqueous slurry of 3-indole aldehyde and N-formyl-indole. The slurry was treated with 38 parts of benzene and the mixture agitated. This treatment with benzene resulted in dissolving of the N-formyl-indole by the benzene and concentration of the 3-indole aldehyde in solid form at the interface of the aqueous, and in the benzene, layer. The aqueous layer was separated and the benzene layer filtered to separate the 3-indole aldehyde. There was obtained 25.5 parts, or 41 per cent of the theoretical yield, of 3-indole aldehyde. The benzene solution obtained as filtrate was analyzed and found to contain 25 parts, or a 40 per cent yield, of N-formyl-indole.

Other modes of applying the principle of the invention may be employed instead of those explained, change being made as regards the method herein disclosed, provided the step or steps stated by any of the following claims or the

equivalent of such stated step or steps be employed.

We therefore particularly point out and distinctly claim as our invention:

1. In a method of making 3-indole aldehyde, the steps of gradually adding indole to an ethereal solution of an alkyl magnesium bromide containing not more than four carbon atoms in the alkyl radical while withdrawing gaseous paraffinic hydrocarbon as it is formed, continuing the addition until the gaseous hydrocarbon is no longer evolved, adding to the resultant ethereal solution of indole magnesium bromide between 0.8 and 2.5 molecular equivalents of an alkyl formate selected from the class consisting of methyl formate and ethyl formate per mole of the indole magnesium bromide, heating the mixture in a closed vessel and at the autogenous pressure to a reaction temperature between 60° and 120° C., hydrolyzing the solid reaction product to form 3-indole aldehyde, and separating the latter.

2. The method, as described in claim 1, wherein the alkyl formate is ethyl formate, between 1 and 1.5 molecular equivalents of ethyl formate is employed per mole of indole magnesium bromide, and the reaction between the indole magnesium bromide and the ethyl formate is carried out at a temperature between 70° and 110° C.

3. In a method of making 3-indole aldehyde, the steps of gradually adding indole to an ethereal solution of an alkyl magnesium bromide containing not more than four carbon atoms in the alkyl radical while withdrawing gaseous paraffinic hydrocarbon as it is formed, continuing the addition until the gaseous hydrocarbon is no longer evolved, adding to the resultant ethereal solution of indole magnesium bromide between 0.8 and 2.5 molecular equivalents of an alkyl formate selected from the class consisting of methyl formate and ethyl formate per mole of the indole magnesium bromide, heating the mixture in a closed vessel and at the autogenous pressure to a reaction temperature between 60° and 120° C., thereafter separating a resultant solid product from the ether, hydrolyzing the product to form a mixture comprising 3-indole aldehyde and N-formyl indole, extracting the latter from the mixture with a liquid aromatic hydrocarbon, and separating 3-indole aldehyde from the remaining mixture.

4. The method which comprises reacting indole magnesium bromide with an alkyl formate selected from the class consisting of methyl and ethyl formates in the presence of diethyl ether as a reaction medium by heating the reaction mixture in a closed vessel at the autogenous pressure to a reaction temperature between 60° and 120° C.

5. A method, as described in claim 3, wherein indole magnesium bromide and between 0.8 and 2.5 molecular equivalents of ethyl formate are employed as reactants and the ethereal reaction mixture is heated in a closed vessel to a reaction temperature between 70° and 110° C.

6. A method, as described in claim 3, wherein indole magnesium bromide and between 1 and 1.5 molecular equivalents of ethyl formate are heated together with diethyl ether in a closed vessel to a reaction temperature between 70° and 110° C.
